UNITED STATES PATENT OFFICE

STATES LEE LEBBY, OF CORNING, NEW YORK.

LIGHT PROJECTOR.

Application filed August 1, 1922. Serial No. 578,963.

To all whom it may concern:

Be it known that I, STATES LEE LEBBY, a citizen of the United States, residing at Corning, in the county of Steuben and State of New York, have invented certain new and useful Improvements in Light Projectors, of which the following is a specification, reference being had therein to the accompanying drawings.

10 My present invention relates to improvements in light projectors and in particular it relates to projection lamps such as are used in railway signals. It is not limited to such use however, being advantageous in other situations where accurately focused light beams are desired.

The prime object of the invention is to provide a highly effective projection lamp with simply constructed means for focusing and 20 aligning the beam of light therefrom in the desired direction.

The invention further includes the novel features of construction and arrangement of parts hereinafter described and particularly defined by the appended claims.

An embodiment of my invention is illustrated in the accompanying drawings in which:

30 Figure 1, is a vertical section taken centrally through the complete lamp or projector; the forward part being broken away and shown in perspective for clearness of illustration.

35 Fig. 2, is a front view, partly in section, and

Fig. 3, is a detail plan view of the means for focusing the lamp.

40 My invention provides means whereby the lamp itself carries a target on which the projected beam may be focused, in the field, without the use of a dark room, and further provides means whereby the focused beam 45 may be accurately directed by the use of simple gun sights, and without the necessity of employing telescopes or complex aligning methods.

Referring now to the accompanying drawings, in my improved construction I have 50 provided a lamp housing 5 of the usual type, but preferably of horizontal cylindrical form, as shown by Figure 1. A reflector or 55 mirror 6 is secured in any suitable manner

in the back of the housing, such as by means of a cover 7 that is detachably fastened to the housing by screws 8 or any other desired means. In securing the mirror in position in the housing, particular care should be used in locating the mirror centrally and squarely in the housing so that the axis of the mirror 60 will coincide with the axis of the housing.

The front of the housing is closed by means of a door 9 carrying a cover glass 10. The door 9 is formed with a circular opening or aperture 11 through which the light 65 beam from the reflector passes, the opening being made of the exact diameter of the normal beam of light at this point, when the beam is properly adjusted. The inner surface of the door around the opening 11 is 70 preferably painted a dull light color, so that the opening is clearly defined when the lamp is being focused, and this portion of the lamp forms a focusing target or screen 12, as will be hereinafter described. Necessarily the 75 axis of the target 12 formed by the door opening is coincident with the axis of the mirror and housing.

The housing 5 has fixed to its front end a sight pin 13, and also fixed to its rear end a 80 peep sight 14. Both of these sights are preferably mounted on the top of the lamp housing as far apart as possible and in the vertical plane of the coincident axes of the reflector, housing and target, and in a horizontal 85 plane parallel to the said coincident axes, whereby the lamp can be sighted and positioned so as to insure the proper direction of the beam.

For the purpose of observing the position 90 of the light beam within the housing 5, with respect to the focusing target 12, a peep hole 15 is formed in the housing 5 near the rear of the lamp and eccentric to the axial line thereof, the peep hole being so angularly disposed that its axis will intersect the center of the opening 11. By looking through the peep hole 15 it is possible to see the focusing target and to properly focus the beam with respect to the target, even in daylight.

100 In focusing the projected beam, it is first spread so that the edge or periphery of the light spot is discernible on the focusing target 12. Then the beam is adjusted so that its projected spot is accurately centered on 105 the target. The spread of the beam is then

reduced by focusing it to the exact diameter of the aperture 11 of the target, this being the predetermined exact normal focus.

I have also provided improved means for accomplishing the necessary focusing and central adjustment of the beam, including a plate 16 slidably disposed on the bottom of the lamp housing 5, and having adjustable pin and slot connections 17 with the lamp housing, such that the plate may be adjusted longitudinally of the lamp, along the line parallel to the axis thereof, and when adjusted, may be clamped in the desired position. Depending from the plate 16 is a hollow tapered extension 18 that passes through an opening 19 formed in the housing 5, and has threaded on to its lower split end, a knurled lock nut 20.

Slidably mounted for vertical adjustment, 20 and for rotary adjustment in the extension 18 of the plate, is the lower tubular end 21 of a hollow vertical standard 22, the upper end of which carries the socket of an electric lamp bulb 23. The portion of the standard 22 above the plate 16, is preferably flattened, as shown, so as to occupy as small a space as possible in the path of the beam projected by the reflector 6.

The lamp or bulb 23 is mounted in the 30 standard 22 in such manner that its filament is off-set from the axis of the standard, so that rotary adjustment of the standard will effect a transverse adjustment of the filament relative to the axis of the reflector.

Wires 24, for supplying electric current to the lamp 23 are passed upwardly through the interior of the hollow standard 22, and are connected to the lamp socket in the usual manner. The lower end of the standard 40 is provided with a knurled head 25 that is designed to be grasped when the lamp is being adjusted within the housing.

The lamp may be first accurately directed by the use of the sights 13 and 14, and the beam then adjusted and focused, or the reverse procedure may be chosen if desired.

The beam can be focused and centered with respect to the focusing target 12 by first unscrewing the lock nut 20 sufficiently 50 to permit the standard 22 to be raised or lowered to bring the lamp filament to the exact vertical position, and rotated to bring the filament to the exact horizontal position desired. This vertical and rotary adjustment will result in the positioning of the filament in the axis of the reflector, and consequently in the axis of the housing and target. For obtaining a movement of the filament axially of the reflector, the plate 16 60 may be adjusted. This plate is adjusted longitudinally of the housing by loosening the pin and slot connections 17, and shifting the plate forward or back until the desired point is obtained. The pin and slot connections may then be tightened to hold

the plate in its adjusted position. It will be understood that after the desired adjustment of the lamp, the lock nut 20 and the pin and slot connection 17, will be tightened up to firmly bind the plate, and with it the standard and lamp in their properly adjusted positions.

From the foregoing it will be seen that by this invention I have provided simple and effective means for bringing to a common axis, the several members of the projectors; i. e., the reflector, the light source, the housing, and focusing target, which necessarily results in bringing the axis of the projected beam to the same common axis, so that the beam, though not discernible beyond the lamp, may be seen in actual function and accurately focused and positioned in the desired direction.

Having thus described my invention what I claim is:

1. In a light-projecting device, the combination of a light source, a concentrating reflector for projecting a signal beam to a distance, a casing containing the light source and reflector, and having an optically open end along the path of the beam, and a target forming a part of the light-projecting device and having an opening of a diameter substantially equal to the normal diameter of the projected beam at the target, for indicating the spread of the beam.

2. In a light-projecting device, the combination of a light source, a concentrating reflector for projecting a signal beam to a distance, a casing containing the light source and reflector, and having an optically open end along the path of the beam, and a target of annular form forming a part of the light-projecting device and located around the axis of the projected beam, for indicating the spread of the beam.

3. In a light-projecting device, the combination of a target centered with respect to the axis of the projector and forming a part of the light-projecting device, and having an opening therein of a diameter substantially equal to the normal diameter of the projected beam at the target, and means for centering the beam on the target and focusing it.

4. In a projector, the combination of a reflector, a cover glass for the projector, and a target arranged between the reflector and the cover glass for indicating the spread of light.

5. A light-projecting device including a light source, a reflector and a casing carrying the light source and reflector, a target forming a part of the structure of the light-projecting device for indicating the spread of light, and located around the axis of the reflector, means for adjusting the light source and focusing and centering the projected beam relative to the target, and sights,

the axis of which parallel the axis of the reflector.

6. In a light-projecting device, a casing, a reflector and a light source carried by the casing, and a target forming a part of the structure of the light-projecting device for indicating the spread of a beam projected by

the reflector, the casing being provided with a peep-hole through which the target may be observed.

In testimony whereof, I hereunto sign my name.

STATES LEE LEBBY.
